UNITED STATES PATENT OFFICE.

ALFRED VEILLETTE, OF ATTLEBORO, MASSACHUSETTS, ASSIGNOR TO SAART BROTHERS COMPANY, OF ATTLEBORO, MASSACHUSETTS, A CORPORATION OF RHODE ISLAND.

BUCKLE.

Application filed August 17, 1923. Serial No. 657,835.

To all whom it may concern:

Be it known that I, ALFRED VEILLETTE, a citizen of the United States, residing at Attleboro, of the county of Bristol and State 5 of Massachusetts, have invented certain new and useful Improvements in Buckles, of which the following is a specification.

My invention relates to improvements in buckles.

One object of my invention is to provide a spring buckle of improved construction especially adapted for use with belts. Not only is the life of the buckle lengthened by easing the strain, vibration, resistance, and jar incident to its use, but much comfort is given the wearer by easing the strain of the belt on his waist. Variation of the strength of the spring may be readily made to suit the needs of the wearer. My invention is 20 peculiarly adapted for men and women engaged in athletics or strenuous professions where much movement of the body is necessary, and is further adapted to give to ease and aid the digestion of a good meal without 25 strain or embarrassment to the wearer, and generally to conform automatically to the varying circumference of the wearer's waist.

A further object of my invention is to dispense with the necessity of material to 30 give elasticity in suspenders, garters, etc., permitting the use of plain cloth, leather, etc., therein, sufficient elasticity being provided by the buckle itself.

A further object of my invention is to 35 provide a spring buckle that may be more readily attached than former types.

A further object of my invention is to 40 provide a buckle of the general type shown provided with means for automatic adjustment thereof for varying strains on the belt and for varying thicknesses of belt.

These and such other objects of my invention as may hereinafter appear will be 45 best understood by the description of one embodiment thereof, such as is shown in the accompanying drawings.

In the drawings, Fig. 1 is a front elevation of my invention with a waist belt attached.

Fig. 2 is a longitudinal section taken along 50 the line 2—2 of Fig. 1.

Fig. 3 is a cross section taken along the line 3—3 of Fig. 2.

Fig. 4 is a perspective view of the pivoted 55 guide plate, and a portion of the toothed belt locking plate.

Fig. 5 is a perspective view of the toothed belt locking plate.

Fig. 6 is a perspective view of the slidable bail plate.

Figure 7 is a perspective view of the modification of the back plate. 60

In the drawings, wherein like characters of reference indicate like parts throughout, 10 generally indicates the buckle. 11 is the back plate thereof with its longitudinal 65 side edges 12 and 13 and ends 14 and 15 flanged outwardly in general box-like formation. One flanged end 14 thereof is provided near the rear portion thereof with a transverse slot 16 for a purpose to be described. An outer shell 17 having longitudinally flanged edges 18, common in buckles of this general type, in the embodiment shown is pivotally mounted on the back plate 11. Said outer shell 17 is adapted to 70 cover up the free end 19 of the belt 20, and may be ornamented, or curved as shown at 21, to conform to the shape of the wearer's body. A pivot bar 22 is mounted in holes 22^a in the flanged side edges 12 and 13 of 80 the back plate 11, the projecting ends 23 of said bar 22 projecting into holes 24 in the side flanges 18 of the outer shell 17. Though I have shown the outer shell pivotally attached to the back plate, it is obvious 85 that it may be detachably or otherwise fastened thereto. I provide means to lock the free end of the outer shell 17 to the back plate 11. In the embodiment shown, these 90 comprise the lugs 25 on the side flanges 18 of the outer shell 17 adapted to register in the holes 26 on the side flanges 12 and 13 of the back plate 11.

I also provide in buckles of this general type means slidably mounted on the back 95 plate to lock the free end 19 of the belt 20 against the outer shell 17 to further engage the belt on tightening thereof and to provide adjustable means to tightly engage the belt with varying thicknesses of belt. To 100 obtain a more perfect adjustment I preferably pivotally mount said slidable means on the back plate 11 as follows: I pivotally mount a guide plate 28 on the back plate 11. Said plate 28 has the sidewise projecting 105 lugs 30 extending from one end thereof adapted to project into suitable holes 31 in the side flanges 12 and 13 on the back plate 11. At each side of the opposite ends thereof I provide projecting straps 33 bent over 110

ovally to form the guide-ways 34. To lock the free end 19 of the belt 20 against the outer shell 17, I provide the belt locking plate 36. As shown in Fig. 5 this comprises 5 a plate having the lugs 38 adapted to register in said guideways 34 projecting sidewise from one end thereof, and the other end thereof being bent outwardly to form the locking lip 39. To more perfectly engage 10 the rough surface of the belt 20, said lip 39 is preferably provided with the teeth 40. A nail rest 41 may be provided on said locking plate 36 to move it readily in the guideways 34. Though I have shown the locking plate 15 36 slidably pivotally mounted on the back plate 11, it is obvious that fairly good results may be obtained by slotting the guide-ways 34 longitudinally of the side flanges 12 and 13 of the back plate 11, and mounting 20 the lugs 38 of the locking plate 36 therein, and providing a short top, reference character 42, on the back plate 11 for the locking plate 36 to bear against as shown in Fig. 7.

As stated, I provide my improved buckle 25 with spring means to ease the functioning thereof. As shown in Fig. 6 I provide the bail plate 43 adapted to slide longitudinally in the base of the back plate 11. The enclosed end 45 thereof is bent outwardly to 30 form the flange 46, and the opposite end thereof terminates in a bail 47 for permanent attachment thereto of one end 49 of the belt 20. When assembled, the bail end 47 of the bail plate 43 projects through the 35 transverse slot 16 in the end flange 14 of the back plate 11, said plate 43 being thus slideable on the back plate 11. I provide spring means to permit resilient movement of the bail plate 43 on the back plate 11, one end of 40 said means registering against the outwardly flanged end 46 of the bail plate 43, and the other end thereof registering against the transversely slotted flanged end 14 of the back plate 11. In the embodiment 45 shown, said means comprises the coil springs 52 and 53. These are preferably provided with guiding means, which in the embodiment shown comprises the bars 50 mounted in holes 56 in the end flanges 14 and 15 of the back plate 11, thus extending longitudinally thereof and through the holes 55 57 in the outwardly bent flange 46 of the bail plate 43.

The operation of my device is obvious 55 from the above description. As stated, one end 49 of the belt 20 is permanently fastened to the bail 47 of the bail plate 43. The free end 19 of the belt 20 is placed around the wearer. The flanged outer shell 17 is released from its locking means to the back plate 11 and swung open. The free end 19 of the belt 20 is then inserted between the toothed outwardly projecting lip 39 of the locking plate 36 and the pivoted end of the outer shell 17. The belt 20 is then tightened

as desired, the locking plate 36 pushed forward in the guideways 34, and the outer shell 17 swung down and locked to the back plate 11. To detach a mere reversal of said operations is necessary. 70

It is obvious that I have not only provided a spring buckle of improved construction, which may be readily used for belts, suspenders, etc., but that I have also provided in buckles of this general type improved means for adjustably locking the free end of the belt thereto. 75

I employ the terms "inwardly" and "outwardly" with reference to the position of the belt on the wearer's body. I use the word "belt" to cover generally any binding member whether it be a garter strap, suspender strap, waist belt, or otherwise. 80

It is understood that my invention is not limited to the specific embodiment shown, 85 and that various deviations may be made therefrom without departing from the spirit and scope of the appended claims.

What I claim as new and desire to secure by Letters Patent, is:

1. In a spring buckle, the combination of a back plate having an outwardly flanged end provided with a transverse slot therein, an outer shell fixedly engageable therewith, a guide plate pivotally mounted on said back plate having longitudinal guideways therein, a locking plate slidably longitudinally mounted in said guideways having a toothed lip to lock the free end of the belt against said outer shell, a bail plate longitudinally slideable on said back plate having one end thereof outwardly flanged and the other end thereof projecting through said transverse slot in said flanged end of the back plate, and terminating in a bail for permanent attachment thereto of a belt end, and spring means extending between the outwardly flanged end of the bail plate and the outwardly flanged end of the back plate. 100

2. In a spring buckle, the combination of a back plate having an outwardly flanged end provided with a transverse slot therein, an outer shell fixedly engageable therewith, means slidably longitudinally pivotally mounted on said back plate for locking the free end of the belt against said outer shell, a bail plate longitudinally slideable on said back plate having one end thereof outwardly flanged and the other end thereof projecting through said transverse slot in said flanged end of the back plate, and terminating in a bail for permanent attachment thereto of a belt end, and spring means extending between the outwardly flanged end of the bail plate and the outwardly flanged end of the back plate. 110

3. In a spring buckle, the combination of a back plate having an outwardly flanged end provided with a transverse slot therein, an outer shell fixedly engageable therewith, 115

- means slidably longitudinally mounted on said back plate for locking the free end of the belt against said outer shell, a bail plate longitudinally slidable on said back plate having one end thereof outwardly flanged and the other end thereof projecting through said transverse slot in said flanged end of the back plate, and terminating in a bail for permanent attachment thereto of a belt end, 5 and spring means extending between the outwardly flanged end of the bail plate and the outwardly flanged end of the back plate.
4. In a buckle, the combination of a back member provided with means for attachment thereto of a belt end, an outer shell engageable therewith, means for detachably locking said outer shell against said back member, and means slidably pivotally mounted on said back plate for locking the 10 free end of the belt against said outer shell.
5. In a buckle, the combination of a back member provided with means for attachment thereto of a belt end, an outer shell engageable therewith, means for detachably locking said outer shell against said back member, and means slidably mounted on said back plate for locking the free end of the belt against said outer shell.
6. In a spring buckle, the combination of a back plate having an outwardly flanged end provided with a transverse slot therein, an outer shell fixedly engageable therewith to lock the free end of a belt therebetween, a bail plate longitudinally slidably mounted 15 on said back plate having one end thereof outwardly flanged and the other end thereof projecting through said transverse slot in said outwardly flanged end of the back plate, and terminating in a bail for permanent attachment thereto of a belt end, and spring means extending between the outwardly flanged end of the bail plate and the outwardly flanged end of the back plate.
7. In a spring belt buckle, the combination of a back plate having its side edges and ends flanged outwardly, and one flanged end thereof transversely slotted near the rear edge thereof, a longitudinally flanged outer shell pivotally attached thereto near 20 the opposite flanged end thereof, lugs on the side flanges of said shell adapted to register in holes in the side flanged edges of said back plate to lock said outer shell thereto, a guide plate pivotally mounted on the side flanged edges of the back plate near the pivot points of said outer shell, provided with straps projecting from the opposite end thereof bent over ovaly to form guideways, a belt locking plate provided with lugs projecting from one end thereof adapted to slide 25 in said guideways, and having its opposite end bent outwardly to form a toothed lip to engage the free end of a belt against said outer shell, a bail plate longitudinally slid- 30 able in the base of said back plate having its enclosed end outwardly flanged and its opposite end projecting through the transverse slot in the aforesaid flanged end of the back plate, and terminating in a bail for permanent attachment thereto of a belt end, 70 coil springs extending longitudinally within said back plate between said outwardly flanged end of the bail plate and the transversely slotted flanged end of the back plate to permit resilient sliding of said bail plate 75 and attached belt end longitudinally of said back plate and guide bars for said coil springs mounted in said flanged ends of the back plate and extending longitudinally of said back plate through holes therefor in the 80 flanged end of the bail plate.
8. In a spring belt buckle, the combination of a back plate having its side edges and ends flanged outwardly, and one flanged end thereof transversely slotted near the rear edge thereof, a longitudinally flanged outer shell pivotally attached thereto near the opposite flanged end thereof, lugs on the side flanges of said shell adapted to register in holes in the side flanged edges of said back plate to lock said outer shell thereto, a belt locking plate pivotally slidably longitudinally mounted on 85 said back plate and having its opposite end bent outwardly to form a toothed lip to engage the free end of a belt against said outer shell, a bail plate longitudinally slidably mounted on the base of said back plate having its enclosed end outwardly flanged and its opposite end projecting through the transverse slot in the aforesaid flanged end of the back plate, and terminating in a bail for permanent attachment thereto of a belt end, 90 coil springs extending longitudinally within said back plate between said outwardly flanged end of the bail plate and the transversely slotted flanged end of the back plate to permit resilient sliding of said bail plate and attached belt end longitudinally of said back plate and guide bars for said coil springs mounted in said flanged ends of the back plate and extending longitudinally of said back plate through holes therefor in the 95 flanged end of the bail plate.
9. In a spring belt buckle, the combination of a back plate having its side edges and ends flanged outwardly, and one flanged end thereof transversely slotted near the rear edge thereof, a longitudinally flanged outer shell pivotally attached thereto near the opposite flanged end thereof, means to lock said outer shell to said back plate, a belt locking plate slidably longitudinally mounted on said back plate and having its opposite end bent outwardly to form a toothed lip to engage the free end of a belt against said outer shell, a bail plate longitudinally slid- 100 able in the base of said back plate having its enclosed end outwardly flanged and its opposite end projecting through the transverse slot in the aforesaid flanged end of the back plate, and terminating in a bail for permanent attachment thereto of a belt end, coil springs extending longitudinally within said back plate between said outwardly flanged end of the bail plate and the transversely slotted flanged end of the back plate to permit resilient sliding of said bail plate and attached belt end longitudinally of said back plate and guide bars for said coil springs mounted in said flanged ends of the back plate and extending longitudinally of said back plate through holes therefor in the 105 flanged end of the bail plate.
10. In a spring belt buckle, the combination of a back plate having its side edges and ends flanged outwardly, and one flanged end thereof transversely slotted near the rear edge thereof, a longitudinally flanged outer shell pivotally attached thereto near the opposite flanged end thereof, means to lock said outer shell to said back plate, a belt locking plate slidably longitudinally mounted on said back plate and having its opposite end bent outwardly to form a toothed lip to engage the free end of a belt against said outer shell, a bail plate longitudinally slid- 110 able in the base of said back plate having its enclosed end outwardly flanged and its opposite end projecting through the transverse slot in the aforesaid flanged end of the back plate, and terminating in a bail for permanent attachment thereto of a belt end, coil springs extending longitudinally within said back plate between said outwardly flanged end of the bail plate and the transversely slotted flanged end of the back plate to permit resilient sliding of said bail plate and attached belt end longitudinally of said back plate and guide bars for said coil springs mounted in said flanged ends of the back plate and extending longitudinally of said back plate through holes therefor in the 115 flanged end of the bail plate.
11. In a spring belt buckle, the combination of a back plate having its side edges and ends flanged outwardly, and one flanged end thereof transversely slotted near the rear edge thereof, a longitudinally flanged outer shell pivotally attached thereto near the opposite flanged end thereof, means to lock said outer shell to said back plate, a belt locking plate slidably longitudinally mounted on said back plate and having its opposite end bent outwardly to form a toothed lip to engage the free end of a belt against said outer shell, a bail plate longitudinally slid- 120 able in the base of said back plate having its enclosed end outwardly flanged and its opposite end projecting through the transverse slot in the aforesaid flanged end of the back plate, and terminating in a bail for permanent attachment thereto of a belt end, coil springs extending longitudinally within said back plate between said outwardly flanged end of the bail plate and the transversely slotted flanged end of the back plate to permit resilient sliding of said bail plate and attached belt end longitudinally of said back plate and guide bars for said coil springs mounted in said flanged ends of the back plate and extending longitudinally of said back plate through holes therefor in the 125 flanged end of the bail plate.
12. In a spring belt buckle, the combination of a back plate having its side edges and ends flanged outwardly, and one flanged end thereof transversely slotted near the rear edge thereof, a longitudinally flanged outer shell pivotally attached thereto near the opposite flanged end thereof, means to lock said outer shell to said back plate, a belt locking plate slidably longitudinally mounted on said back plate and having its opposite end bent outwardly to form a toothed lip to engage the free end of a belt against said outer shell, a bail plate longitudinally slid- 130 able in the base of said back plate having its enclosed end outwardly flanged and its opposite end projecting through the transverse slot in the aforesaid flanged end of the back plate, and terminating in a bail for permanent attachment thereto of a belt end, coil springs extending longitudinally within said back plate between said outwardly flanged end of the bail plate and the transversely slotted flanged end of the back plate to permit resilient sliding of said bail plate and attached belt end longitudinally of said back plate and guide bars for said coil springs mounted in said flanged ends of the back plate and extending longitudinally of said back plate through holes therefor in the flanged end of the bail plate.

through the transverse slot in the aforesaid flanged end of the back plate, and terminating in a bail for permanent attachment thereto of a belt end, coil springs extending longitudinally within said back plate between said outwardly flanged end of the bail plate and the transversely slotted flanged end of the back plate to permit resilient sliding of said bail plate and attached belt end longitudinally of said back plate and guide bars for said coil springs mounted in said flanged ends of the back plate and extending longitudinally of said back plate through holes therefor in the flanged end of the bail plate.

10. In a belt buckle, the combination of a back plate having its side edges and ends flanged outwardly provided with means on one end thereof for permanent attachment thereto of a belt end, a longitudinally flanged outer shell pivotally attached thereto near the opposite flanged end thereof, means to lock said outer shell to said back plate, a guide plate pivotally mounted on the side flanged edges of the back plate near the pivot points of said outer shell provided with straps projecting from the opposite end thereof bent over ovally to form guideways, and a belt locking plate provided with lugs projecting from one end thereof to slide in said guideways and having its opposite end bent outwardly to form a toothed lip to engage the free end of a belt against said outer shell.

35. 11. In a belt buckle, the combination of a back plate having its side edges and ends flanged outwardly, provided with means on one end thereof for permanent attachment thereto of a belt end, a longitudinally flanged outer shell pivotally attached thereto near the opposite flanged end thereof, means to lock said outer shell to said back plate, and a belt locking plate longitudinally slidably mounted on said back plate, and having its opposite end bent outwardly to form a toothed lip to engage the free end of a belt against said outer shell.

40. 12. In a spring belt buckle, the combination of a back plate having its side edges and ends flanged outwardly, and one flanged end thereof transversely slotted near the rear edge thereof, a longitudinally flanged outer shell pivotally attached thereto near the opposite flanged end thereof, and fixedly engageable therewith to lock the free end of a belt therebetween, a bail plate longitudi-

nally slidable in the base of said back plate having its enclosed end outwardly flanged and its opposite end projecting through the transverse slot in the aforesaid flanged end 60 of the back plate, and terminating in a bail for permanent attachment thereto of a belt end, coil springs extending longitudinally within said back plate between said outwardly flanged end of the bail plate, and the 65 transversely slotted flanged end of the back plate to permit resilient sliding of said bail plate and attached belt end longitudinally of the said back plate and guide bars for said coil springs mounted in said flanged 70 ends of the back plate and extending longitudinally of said back plate through holes therefor in the flanged end of the bail plate.

13. In a buckle, the combination of a back plate provided with means for attachment thereto of a belt end, and having a toothed lip projecting outwardly therefrom, an outer shell and means for detachably locking said outer shell to said back plate and against said toothed lip, whereby the free end of a 80 belt may be locked between said toothed lip and said outer shell.

14. In a buckle, the combination of a back member provided with means for attachment thereto of a belt end, and having a toothed lip projecting outwardly therefrom, an outer shell pivotally attached thereto, and means to lock the unpivoted end of said outer shell to said back plate whereby the free end of the belt may be locked between 90 said outer shell and the toothed lip of the back member.

15. In a buckle, the combination of a back plate provided with means for attachment thereto of a belt end, and having a lip projecting outwardly therefrom, an outer shell and means for detachably locking said outer shell to said back plate and against said toothed lip, whereby the free end of a belt may be locked between said lip and said 100 outer shell.

16. In a buckle, the combination of a back member provided with means for attachment thereto of a belt end, and having a lip projecting outwardly therefrom, an outer shell pivotally attached thereto, and means to lock the unpivoted end of said outer shell to said back plate whereby the free end of the belt may be locked between said outer shell and the lip of the back member.

In testimony whereof I affix my signature.

ALFRED VEILLETTÉ.
